United States Patent Office

Des. 225,180

Patented Nov. 21, 1972

225,180

PORTABLE PIANO

George H. Weber, Seattle, Wash., and Robert Collins, Los Angeles, Calif., assignors to The Weber Corporation, Seattle, Wash.

Filed Feb. 26, 1971, Ser. No. 119,450

Term of patent 14 years

Int. Cl. D17—01

U.S. Cl. D56—9

FIG. 1

FIG. 2

FIG. 3

FIG. 4

FIG. 5

FIG. 6

FIG. 1 is a perspective view of a portable piano in its open operative position showing our new design;

FIG. 2 is a perspective view showing the portable piano of FIG. 1 in its closed position for transporting purposes;

FIG. 3 is a top plan view of FIG. 1;

FIG. 4 is a rear elevation view of FIG. 3;

FIG. 5 is an underside plan view taken along the line 5-5 of FIG. 4; and

FIG. 6 is an end elevation view of FIG. 1.

We claim:

The ornamental design for a portable piano, substantially as shown and described.
